[57] CLAIM

The ornamental design for storage drawers, as shown and described.

DESCRIPTION

FIG. 1 is a perspective view of a storage drawer unit showing our new design;

FIG. 2 is a top plan view thereof;

FIG. 3 is a front elevational view thereof;

FIG. 4 is a right side elevational view thereof, the opposite side view being a mirror image thereof;

FIG. 5 is a rear elevational view thereof;

FIG. 6 is a bottom plan view thereof;

FIG. 7 is a perspective view of a second embodiment of FIG. 1 thereof;

FIG. 8 is a front elevational view of FIG. 7 thereof;

FIG. 9 is a rear elevational view of FIG. 7 thereof;

FIG. 10 is a bottom plan view of FIG. 7 thereof;

FIG. 11 is a third embodiment of FIG. 1, with the embodiment of FIG. 1 in a stacked position thereof; and,

FIG. 12 is a front elevational view of FIG. 11 thereof.
